DESIGN FOR A TIE RACK

Joseph Lester, New York, N. Y.

Application February 1, 1945, Serial No. 117,716

Term of patent 14 years

(Cl. D33—8)

To all whom it may concern:

Be it known that I, Joseph Lester, a citizen of the United States of America, residing in New York, county of New York, and State of New York, have invented a new, original, and ornamental Design for a Tie Rack, of which the following is a specification, reference being had to

the accompanying drawing, forming part thereof.

The figure on the drawing is a perspective view of a tie rack showing my new design.

I claim:

The ornamental design for a tie rack, substantially as shown.

JOSEPH LESTER.
